UNITED STATES PATENT OFFICE.

JACOBUS SIMON DE ROOS, OF AMSTERDAM, NETHERLANDS.

VAPORIZING DEVICE FOR INTERNAL-COMBUSTION ENGINES.

No. 904,455.

Specification of Letters Patent.

Patented Nov. 17, 1908.

Application filed January 27, 1908. Serial No. 412,872.

To all whom it may concern:

Be it known that I, JACOBUS SIMON DE Roos, a subject of the Queen of the Netherlands, and residing at Amsterdam, Netherlands, have invented certain new and useful Improvements in Vaporizing Devices for Internal-Combustion Engines, of which the following is a specification.

This invention relates to a device for introducing liquid fuel in a completely evaporated, superheated and highly compressed state into the engine cylinder of internal combustion engines, and chiefly consisting of an evaporating chamber arranged separately in the head of the cylinder.

The characteristic feature of the device is that the evaporating chamber which at the same time forms a mixing chamber, is normally not open to the interior of the cylinder. During the suction stroke, the fuel is supplied to the chamber through a valve or forced in by a pump or in some other way. During the compression stroke, compressed air enters the chamber from the cylinder through an automatic valve. In that way, already during the whole compression stroke, an evaporation, superheating and a preliminary combustion are obtained bringing about a considerable increase of pressure in the chamber. After the opening of a valve, the whole quantity of fuel will, therefore, pass into the engine cylinder in a completely gasified and superheated state.

A construction according to this invention is illustrated by way of example in the accompanying drawing, in which

Figure 1 is a vertical section, Fig. 2 a horizontal cross-section on line A—B of Fig. 1, Figs. 3 and 4 horizontal cross-sections respectively on lines C—D and E—F of Fig. 1, Fig. 5 shows diagrammatically the construction and the arrangement of the valve gear disk.

The casing 1 is arranged in the well known manner in the cylinder cover 2. The bottom portion of the casing is provided with a cylindrical chamber 3. This chamber is closed at the bottom by a screw plug 4 provided with a perforation 5 and at the same time forms the seat for the needle valve spindle 6.

The plug 4 is secured by means of a cover or cap 7 with a counter-sunk resistance regulator 8. The resistance regulator consists of a cylindrical pin 8 pointed at both

ends and provided with a coarse flat screw-thread. The casing is held in place by means of a cover or retaining part 29 having its lower end of a conical shape. The cover 29 and the casing are provided in a suitable manner with three perforations intended to act respectively as a fuel supply conduit 9, a guide for the needle valve spindle 6 and a perforation for the air valve casing 10. The valve spindle 6 is guided by means of a stuffing box arranged at the top in the cover 29, and in a casing 11 arranged on the said cover. The said valve spindle is preferably provided with a fixed stop 12 while a helical spring arranged in the casing 11 has the constant tendency to force the needle point of the spindle 6 into the perforation 5 of the screw plug forming its seat. The air valve casing 10 is provided with an automatic valve 13 which closes the communication between the cylindrical chamber 3 and the engine cylinder 28 through two conduits 14 and 15 formed in the casing 1. In the conduit 14, moreover a ball-valve 30 is provided to close the communication between the conduit and the cylinder.

The fuel supply conduit 9 communicates by a passage 16 with the cylindrical chamber 3 and is closed by a second needle valve 17. The fuel supply pipe is connected to the fuel supply conduit in well known manner, and moreover, arrangement is also made for the escape of air (Fig. 1). The spindle 17 of the needle valve is guided in a suitable manner in the casing 1 and in the cover 29, and under the influence of spring pressure, keeps the conduit 16 closed.

The spindle 6 and the spindle 17 are operated in the following manner:—At a suitable level, not given however in the drawing, the cover 29 is provided with a bell crank lever 18 which is operated in a suitable manner by a roller 19 and the valve gear cam disk 20 (Fig. 5). The free end of the crank lever surrounds the valve spindle 6 and in normal position is in contact with the stop 12 of the same. Let the different positions which the roller can occupy on the circumference of the valve gear cam disk 20 be marked I to V. The valve gear cam disk itself is provided on its periphery with a short projection 21, a longer projection 22 and a recess 23. On the casing 11 arranged on the pressure part is rotatably mounted a short lever 24 (Figs. 1 and 2) of which one end carries a projection 25 opposite which

the bell crank lever 18 is provided with a boss 26, while the other end of the short lever 24 engages with the spindle 17. The latter always normally keeps the fuel passage 16 closed by means of a helical spring. In Fig. 1 the piston 27 is shown in its highest position in the working chamber 28.

The working of the new device is as follows:—The piston is supposed to be at its highest position in the cylinder, the fuel conduit 9 is assumed to be filled in well known manner and any air removed and all the valves closed. During the suction stroke, the positively operated valve 6 is raised till about the middle of the stroke, and thus opens communication between the cylinder and the cylindrical chamber 3 so that a rarefaction of the air in the said chamber 3 is brought about. Then the valve 6 closes and the valve 17 opens, whereby a small quantity of fuel is admitted into the chamber 3. During this second portion of the suction stroke the air admission valve to the cylinder is opened. At the end of the suction stroke the fuel passage 16 is again closed by the fuel needle valve. The valve spindle 17 may be controlled in well known manner, not shown in the drawing, by a governor, so that the fuel supply is regulated according to requirements. During the subsequent compression stroke, the needle valves 6 and 17 remain in their closed position. A portion of the heated compressed air after lifting the ball valve 30 escapes then through the passage 14, opens the automatic valve 13 and penetrates through the passage 15 into the cylindrical chamber 3. This incoming air becomes thoroughly mixed with the fuel contained in the chamber 3 and brings about its complete evaporation, superheating and preliminary combustion. This vaporizing results in such a great increase of pressure that the automatic valve 13 is again closed and remains closed during further compression until the pressure in the cylinder or conduit space 14 becomes greater than the pressure in the chamber 3. Then another considerably hotter air-jet is forced into the chamber 50 and the fuel mixture is heated to a still greater extent. The object of the ball-valve 30 is to prevent the highly heated air passing back through the conduit space 14. These injections of air are repeated up to the end of the compression stroke and bring about a complete evaporation and superheating, and more particularly the last injections effect a preliminary combustion of the quantity of fuel in the chamber 3, whereby the pressure and the temperature in the same are increased to such an extent as to considerably exceed those in the working chamber. A preliminary combustion of the fuel may be effected also by an igniter arranged in the chamber 3.

At the dead point of the piston the positively controlled valve 6 is raised, and the completely evaporated, superheated and preliminarily burned quantity of gas, owing to its considerably greater pressure, escapes through the perforation 5 and through the resistance regulator 8 arranged in the cover 7, into the working chamber. Then a combustion takes place in accordance with the constant pressure or explosion process. In order completely to balance the excess of pressure in the chamber 3, the pin 6 is closed only at the end of the combustion stroke. Owing to the said pin remaining raised, the chamber 3 receives a rinsing of the air contained behind the ball valve in the chamber 14. The exhaust of the combustion gases is effected in the well known manner. The fuel may also be introduced during the compression stroke into the chamber 3.

The positive movement of the two needle valves takes place in the following manner:—At the beginning of the suction stroke the two valves under the action of their springs are closed and the roller 19 is in the dotted position I (Fig. 5.) The short lever 24 is in contact with the boss 26 by means of its projection 25 (Fig. 1.) During the suction stroke the cam disk rotates in the direction of the hands of a watch the short projection 21 raises the roller 19 and therefore the bell crank lever 18 which, by means of the stop on its spindle 12 raises the spindle 6. About the middle of the suction stroke the roller 19 arrives into the position V whereupon the valve spindle 6 is lowered and the passage 5 closed.

During the further movement of the roller 19, that is to say, during the second portion of the suction stroke, the said roller travels along the recess 23 whereupon the lever 18 is moved downwards, the spindle 6 is left in place, but the boss 26 on the crank lever depresses the finger 25 whereupon the left hand end of the lever 24 and consequently the spindle fuel pin 17 are moved upwards. At the end of the suction stroke the roller 19 is again in its normal position (position II) and the fuel needle valve has again closed. From the dead point III the bell crank lever 18 and with it the spindle 6 are raised by the longer projection 22 on the cam disk, during the whole combustion stroke, so that the contents of the chamber 3 can escape into the cylinder 28. In the position IV that is to say, at the end of the working stroke, the crank lever 18 is brought back to its original position and during the movement from IV to I while the expulsion of the combustion gases takes place the two needle valves 6 and 17 are held closed by the pressure of the springs. Owing to the complete vaporization, superheating and preliminary combustion of the fuel which is strongly superheated owing to the injections of hot air taking place during

the compression stroke and forms a very explosive mixture, the advantage is obtained that any kind of fuel including heavy and light ones and the like may be used. When 5 the mixture passes into the cylinder, a complete combustion at once takes place and in this way the highest temperature is obtained at the moment of admission of the mixture. It will thus be seen that a considerably lower 10 temperature is thus obtained at the end of the combustion stroke, than is the case in known constructions of internal combustion engines, where the heat required for the vaporizing and combustion of the fuel, is given off 15 only after the admission of the fuel, into the cylinder, so that the highest temperature in the known constructions is reached at a later period and consequently the end temperature is correspondingly higher. The thermic efficiency 20 of motors with the new device is therefore considerably greater than that of known constant pressure motors or internal combustion engines.

What I claim as my invention and desire 25 to secure by Letters Patent is:—

1. The combination of an internal combustion engine comprising a cylinder having a piston to operate therein, and a casing provided with a mixing chamber, an outlet 30 valve for normally closing communication between said chamber and cylinder, a valve providing means for admitting fuel into the chamber, means for opening said outlet valve during a portion of the suction stroke 35 of the piston to reduce the pressure within said chamber, means for opening said fuel valve after the closing of said outlet valve to admit a charge of fuel into said chamber, means for admitting air from the cylinder 40 during the compression stroke of its piston into said chamber, and means for opening said outlet valve to discharge the mixed and superheated gas from said chamber into the cylinder.

2. The combination of an internal combustion engine comprising a cylinder having a piston to operate therein, a casing attached to the cylinder and provided with a mixing chamber, an outlet valve for normally closing 50 communication between said chamber and cylinder, a valve providing means for admitting fuel into said chamber, an automatically operating air valve providing means for conducting heated air from the cylinder during the compression stroke of its piston into said chamber, and valve controlling mechanism for opening said outlet

valve during a portion of the suction stroke of the piston and for closing said valve and opening the fuel inlet valve during a remaining portion of the suction stroke to admit a charge of fuel into said chamber, said valve mechanism serving also to open said outlet valve preparatory to the power stroke of the piston to discharge the vaporized and superheated gas from said chamber into the cylinder. 60 65

3. The combination of an internal combustion engine comprising a cylinder having a piston to operate therein, a casing fitted to 70 said cylinder and provided with a mixing chamber, an outlet valve normally closing communication between said chamber and cylinder, a fuel valve for conducting a charge of fuel into said chamber, an air 75 valve for automatically admitting charges of heated air from the cylinder during the compression stroke of the piston into said chamber, a cam disk, a lever operatively connected to the outlet valve for opening it during a 80 portion of the suction stroke of the piston and during the power stroke thereof, said lever being controlled by said cam, and a second lever operatively connected to the fuel valve and arranged to be engaged by the 85 lever first mentioned to open the fuel valve after the closing of the outlet valve upon the suction stroke of the piston.

4. The combination of an internal combustion engine comprising a cylinder having 90 a piston to operate therein, a casing fitted into the cylinder and provided with a mixing chamber having a passage forming communication between it and the cylinder, an outlet valve normally closing said passage, a 95 fuel inlet valve for conducting charges of fuel into said chamber, means for conducting air into said chamber to form a superheated explosive mixture therein, and a resistance regulator arranged in said outlet passage between the mixing chamber and cylinder, said 100 regulator comprising a pin pointed at each end and provided with a peripheral thread adapted to impinge upon the gas escaping from said chamber and thus retard the passage of the mixed gas into the cylinder. 105

In testimony whereof I have signed my name to this specification in the presence of two subscribing witnesses.
